(57) **CLAIM**

The ornamental design for a trigger for a trigger sprayer, as shown and described.

DESCRIPTION

FIG. 1 is a front elevation view of a trigger for a trigger sprayer;

FIG. 2 is a rear elevation view of the trigger;

FIG. 3 is a right side elevation view of the trigger, the left side elevation view being a mirror image thereof;

FIG. 4 is a top plan view of the trigger;

FIG. 5 is a bottom plan view of the trigger;

FIG. 6 is a front perspective view of the trigger;

FIG. 7 is another front perspective view of the trigger; and,

FIG. 8 is a rear perspective view of the trigger.
